GEORGE H. MILLER, OF MILWAUKEE, WISCONSIN, ASSIGNOR TO METAL FORMS CORPORATION, OF MILWAUKEE, WISCONSIN, A CORPORATION

STAKE BOX

Application filed February 20, 1929. Serial No. 341,518.

The now known methods of fastening a stake box to a road rail involve the forming of one or more slots in the rail, and through the medium of these slots interlocking the stake box to the said rail by engaging interlocking means on the stake box with the rail. The connection between the stake box and the rail is completed by fastening the box at its lower portion to the base of the rail, riveting being the conventional method of setting up this connection.

Such a connection as briefly outlined above has been recognized by engineers in the road building art and is highly desirable, but there are certain unfavorable features which I propose to obviate by this invention. I note that the interlocks between the stake boxes and rail now availed of in setting up the connection between these two, in every case involve a weakening of the rail due to the presence of at least one slot therein which is only partially filled by the hook means carried by the stake box. In view of this condition, an object of this invention is to provide a stake box with suitable means for engaging a rail by passing through the slots therein, and which means will completely fill the slots in which they are inserted in creating the interlock.

The above noted end is achieved by providing the stake box with outwardly extending projections that are turned over to provide hooks or arms that engage the rail. The outwardly extending portions of the arms are dimensioned so that they will nicely fill out the slot in which the hooks are inserted. In order to bring the hooks in proper position, it is necessary that they be inserted in the slots in the rail and then the box brought into its final position with a swinging action which is accompanied by wedging of the projection in the slot. It is apparent, therefore, that an important feature of the invention resides in the method by which the box and rail are assembled, particular emphasis being placed on this swinging wedging action. When the box has been swung into its final position it is held therein by fastening the feet thereof to the base of the rail.

It is a further object of the invention to provide a stake box of the character above

noted in which the hook members are designed to act as a reinforcement for the carrying surface of the rail. This end is attained by properly dimensioning the hook members so that when they are swung into position they will engage the underside of the carrying surface of the rail and reinforce the same. Furthermore, an important feature of this arrangement resides in the fact that the stresses applied to the box are transmitted to the top of the rail and this overcomes the tendency of the metal of the adjacent rail wall to buckle owing to the coaction of the box with the said wall intermediate its height.

When a stake box is affixed to a rail in accordance with the above noted ideas, it is not liable to become disengaged from the rail due to the presence of heavy loads on the latter. This tendency is always present in the now known types of rail because a relative downward movement of the top of the rail with the base thereof tends to disengage the types of interlocking means now employed at this point.

With these and other objects and advantages in view, the invention comprises certain other constructions, combinations, and arrangements of parts as will be hereinafter specified and claimed.

For a full and more complete understanding of the invention, reference may be had to the following description and accompanying drawings, in which

Figure 1 is a perspective showing of my novel stake box mounted on a rail.

Figure 2 is a vertical section taken about on the line 2—2 of Figure 1 bringing out the connection between the stake box and the rail.

Figure 3 is a view in side elevation showing how the lugs of the stake box are brought into engagement with the complementary slots in the rail.

Figure 4 is a perspective view of the preferred form of my novel stake box.

Figure 5 is a side elevation of a stake box mounted on a rail, showing one modification of my invention.

Figure 6 is a similar view to Figure 5 showing another form of my novel stake box.

While a preferred and more specific em-

bodiment of the invention is herein set forth, it is to be understood that I am not to be limited to the exact constructions illustrated and described, because various modifications of these details may be provided in putting the invention into practice within the purview of the appended claims.

Referring now to Figure 1, a conventional type of road rail generally designated as A is formed with upstanding side members 1 and 2 joined together at their tops by a curved portion 3. The lower portion of the side member 2 is bent outwardly therefrom to form a flange 5, while the lower portion of the side member 1 is bent inwardly to form a flange 4 which extends under the side member 2 and is parallel and adjacent to the aforementioned flange 5. An opening 6 through the flanges 4 and 5 is adapted to receive a stake 7 therethrough. Slots 8 are provided in the side member 2 for reasons to be hereinafter set forth.

A stake box built in accordance with my invention as shown in Figure 4 comprises side members 9 and 10 integral with a joining member 11. Lugs 12 project outwardly and upwardly from the side members 9 and 10 substantially as shown. An aperture 13 in the member 11, similar to the opening 6 in the rail A, is adapted to receive the stake 7. The lower parts of the side members 9 and 10 are bent outwardly into flanges or feet that are parallel and adjacent to the flange 5 of the rail A when the stake box is in its assembled position. Openings 14 in these feet are adapted to receive rivets for peaning the box to the rail. Near the junction of the members 9 and 10 with the member 11, are slots 15 for receiving a wedge 16.

In fastening my novel stake box to a rail, the upper ends of the lugs 12 are first inserted in the slots 8, the box being held in a position substantially at right angles to its final intended position. The whole box is then swung downwardly with the lugs 12 and slots 8 forming a pivot as clearly shown in Figure 3. It can be clearly seen from the drawings that when the box is in its intended position, the feet of the side members 9 and 10 abut against the flange 5 of the rail while the shoulders of the lugs 12 are thrust upwardly against the ends of the slots 8. Any possible up and down motion of the box is thereby prohibited and the box acts as a stiffener or rib for the side member 2 of the rail A. Rivets are then fastened through the feet of the members 9 and 10 and the flanges 4 and 5 thereby holding the box in place. The stake 7 and wedge 16 are then applied as shown in the drawings.

Figure 6 shows a modification of my novel stake box wherein lugs 17 are made of greater length than the lugs 12 of the preferred form. When the stake box is positioned, the ends of the lugs 17 abut against the under-side of the

curved portion 3 of the rail A thereby giving additional strength to the member 3.

Another modification of my stake box is shown in Figure 5. In this form, the shoulders denoted at 18 do not extend above the member 11. A slot 19 in the shoulder 18 is adapted to engage the slot 8 in the side member 2 and prevents the stake box from moving away from the rail A.

Although in this last modification, part of the slot 8 is left unfitted by the member 18, it is desired to once more point out that in all of the forms the lower part of the box abuts the flange 5 of the rail and the lugs or shoulders formed thereby thrust upwardly against the ends of the slots 8 thereby preventing any up and down movement of the box on the rail. This novel construction wherein the box is wedged into position gives a stiffening effect to the rail heretofore unattained in a box adapted to be placed in position in the field.

Having thus described my invention, what I claim as new and desire to secure by Letters Patent of the United States, is—

1. In a road rail construction of the class described, the combination with a rail comprising a side member having a slot therein, of a stake box including a vertical wall substantially at right angles to the side member of the rail, and fastening means between the box and rail comprising a projection on the vertical wall of the box which completely fills the slot in the rail, the base of the stake box abutting with the base of the rail so that the box forms a brace for the rail.

2. A road rail comprising a substantially vertical side member having a vertical slot, a stake holding device comprising a vertically arranged member at right angles to and fitting against the side member of the rail, the said member of the stake holding device having a vertical projection extending inwardly through the slot of the rail side member and upwardly on the inner face thereof, and means attaching the said stake holding device to the base of the rail so that the said device forms a vertical brace edgewise to the rail and interlocked to its side member to render the latter more rigid than afforded by its own structure.

3. A road rail comprising a base from which upwardly extends a vertical side member bent laterally to form a head and downwardly to form a second substantially vertical side member having a vertical slot, a stake holding device comprising a vertically arranged member at right angles to and fitting against the side member of the rail, said member of the stake holding device having a vertical projection extending inwardly through the slot of the rail side member and upwardly on the inner face thereof until it engages the under side of the head of the rail so as to act as a brace upwardly against the head, and

means attaching the said stake holding device to the base of the rail so that the said device forms a vertical brace edgewise to the rail and interlocked to its side member to render the latter more rigid than afforded by its own structure.

In testimony whereof I affix my signature.

GEORGE H. MILLER.
